CLAIM

The ornamental design for a garage parking location marker, as shown and described.

DESCRIPTION

FIG. 1 is a front elevational view of a garage parking location marker showing my new design, with the cords and hook broken away to indicate indeterminate length; FIG. 2 is a side elevational view thereof; the opposite side view is a mirror image thereof; FIG. 3 is a bottom plan view thereof; FIG. 4 is a top plan view thereof; and, FIG. 5 is a rear elevational view thereof.
